(57) **CLAIM**

The ornamental design for a medical device for optically measuring physiological signals as shown and described.

DESCRIPTION

FIG. 1 is a perspective view thereof from a front angle;

FIG. 2 is a perspective view thereof from a rear angle;

FIG. 3 is a front elevation view thereof;

FIG. 4 is a rear elevation view thereof;

FIG. 5 is a first side elevation view thereof;

FIG. 6 is a second side elevation view thereof, opposite the first side;

FIG. 7 is a top plan view thereof; and,

FIG. 8 is a bottom plan view thereof.

The broken lines in the drawings of a removable tip for use with the device depict environmental subject matter and form no part of the claimed design.

1 Claim, 8 Drawing Sheets
